ATTORNEY.

UNITED STATES PATENT OFFICE

140,357

DESIGN FOR A TARGET GAME BOARD

Henry C. Hitzeman, Chicago, Ill., assignor to
Henry C. Hitzeman, Harold C. Jeske, and Henry
Elton Pease, all of Chicago, Ill.

Application May 15, 1944, Serial No. 113,600

Term of patent 14 years

(Cl. D34—5)

To all whom it may concern:

Be it known that I, Henry C. Hitzeman, a citizen of the United States, residing at Chicago, in the county of Cook and State of Illinois, have invented a new, original, and ornamental Design for a Target Game Board, of which the following is a specification, reference being had to the accompanying drawing forming a part thereof.

In the drawing:

Fig. 1 is a front elevational view of a target game board showing my new design, and

Fig. 2 is an edge view thereof.

I claim:

The ornamental design for a target game board, as shown.

HENRY C. HITZEMAN.
